JOHN T. PHIPPS, OF HUNTINGTON PARK, CALIFORNIA, ASSIGNOR TO H. C. SMITH MANUFACTURING COMPANY, OF WHITTIER, CALIFORNIA, A CORPORATION OF CALIFORNIA

CORE CATCHER CONSTRUCTION

Application filed September 27, 1929. Serial No. 325,572.

This invention relates to a core bit and appertains especially to a core catcher unit to retain the core captured in the core barrel. It is the common practice to provide core bits with rings disposed adjacent the mouth of the barrel and having longitudinally extending spring fingers.

An object of this invention is to provide such a core catcher with fingers and a supplementary gripping ring to grab the core out upon downward pressure on the fingers and aid in holding the core in the core barrel. In addition to the broader object of this invention, there are certain details of design whereby a simple, economical and compact core catcher unit is obtained and one which is certain in its functioning.

These objects together with other objects and corresponding accomplishments are obtained by means of the embodiment of my invention illustrated in the accompanying drawings, in which:—

Fig. 1 is an elevation of a core bit and barrel partly in section to better show the core catcher unit and its relation to the other elements of the core bit and barrel; Fig. 2 is a section showing a fragment of the core bit with my improved catcher unit; and Fig. 3 is a plan view partly in section of the core catcher unit.

Referring more particularly to the drawings, 5 indicates a core bit having laterally extending blades and an annular crown cutter. It is provided with a tapered threaded socket at the top to receive a barrel 6 provided with a threaded pin 7 for attachment to a drill pipe string. The construction just described is a standard type of core bit and barrel and forms no parts of the present invention. A chamber is formed in the core bit and at its lower end is a tapered seat 8. The upper end of the chamber is internally threaded to receive a core retainer tube 9. It may be remarked that the core barrel as shown herein is relatively short and is so shown for compactness of the view. In practice, the barrels are relatively longer to take a relatively long core. The core taken is of considerable weight.

50 An annular recess is formed between the

seat 8 and the bottom of the tube, in which is disposed a core catcher ring 10. Depending from the ring are spring leaves 11 which are attached to the sections of a contractible gripping ring 12. The ring 12 is in the 55 nature of slips commonly used in well work for gripping various articles. This contractible ring has tapered outer wall for riding upon the seat 8. However, when the ring is fully contracted so that the junctures of the sections meet, it is externally 60 of a size such that it will not pass through the mouth of the core bit.

The length of the unit formed by the core catcher ring and the gripping ring together 65 with their associated elements is such that they may have a limited longitudinal movement. The gripping ring is provided with annular corrugations 13 for obtaining a hold upon the core. Attached to the inner 70 wall of the catcher ring are fingers, each finger being shown as comprising two spring leaves 14a and 14b. It will be understood that more leaves may be used if desired. The leaves of a finger are secured at their 75 roots to the catcher ring 10 by rivets 15 or any other fastening device found expedient.

The outward flexure pressure of the leaves 11 tend to maintain the core catcher unit in the position shown in Fig. 2. The annular 80 recess provides a bearing for the core catcher unit so that it may be rotated with respect to the bit. The core being cut passes upwardly through the gripping ring and between the fingers which engage the side 85 of the core. As the core bit and barrel are elevated to withdraw the core cut, the tips of the fingers resist the movement of the core downwardly out of the barrel. As shown, there are a plurality of leaves in the 90 fingers to resist downward pressure, and relieve the strain at their roots aiding one another so as to resist breakage. Furthermore, a greater contact area is provided by 95 reason of a plurality of tips. The core is grasped at points spaced from one another. The weight of the core acting downwardly will cause contraction of the gripping ring 12 and to aid in supporting the core. 100

What I claim is:—

1. The combination with a core bit and barrel having a recess in the bore thereof for a core catcher unit and having a tapered seat; of a core catcher longitudinally slideable in said recess; said core catcher unit including a core catcher ring, resilient catcher fingers upstanding from said ring with the tips free and directed inwardly, said fingers comprising multiple spring leaves with the tip ends of said leaves longitudinally spaced, a contractible gripping ring depending from and secured to said core catcher ring and having faces riding on said seat for expansion and contraction of said gripping ring upon longitudinal movement of said unit.

2. The combination with a core bit and barrel having a recess in the bore for a core catcher unit; of a core catcher unit including a core catcher ring, multiple spring leaf catcher fingers secured at their bases to said ring and free at their upper tip ends, the tip ends of the leaf springs being longitudinally spaced and directed inwardly.

3. The combination with a core bit and barrel of a core catcher mounted in said bore comprising multiple leaf spring fingers secured at their bases and free at their tip ends, the tip ends of the spring leaves being longitudinally spaced and directed inwardly to provide a multiplicity of core engaging ends.

In witness that I claim the foregoing I have hereunto subscribed my name this 7th day of September, 1929.

JOHN T. PHIPPS.
